Application April 26, 1947, Serial No. 744,143

5 Claims. (Cl. 315—39)

1

This invention relates to an electron-discharge device in which electrons are caused to react with an electromagnetic wave in a waveguide so as to give up energy to said wave or to abstract energy therefrom. In the first case the device could be made to operate as an amplifier, oscillator, or the like, while in the second case the device could act as an electron accelerator.

Heretofore, the velocity, at which the phase of a wave radiated through a waveguide progresses along a direction parallel with the longitudinal axis of the guide, has been termed the phase velocity of the guide for the particular wave under consideration. Such phase velocity, which will hereafter be characterized as the linear phase velocity, is, in the case of a simple waveguide, in excess of the speed of light, which it approaches as a limit. In order for an electron to react in the manner described above, it is necessary to preserve the electron in a substantially fixed position relative to the phase of the wave throughout substantially the entire travel of the electron through the device, since otherwise the electron at one time would be imparting energy to the wave and at another time would be abstracting energy therefrom, giving a substantially zero net effect. It is impossible to cause the electron to travel at the linear phase velocity of a simple waveguide, since, as pointed out above, such velocity is in excess of the velocity of light.

An object of this invention is to cause an electron to travel along such a path in a waveguide as to preserve a substantially constant phase relation with respect to a wave therein whose linear phase velocity exceeds the velocity of light.

Another object of this invention is to devise an arrangement in which such constant phase relation exists and which operates as an amplifier of microwaves.

A further object of this invention is to produce a device of this kind which operates as an electron accelerator.

A still further object is to devise an arrangement for causing an electron to travel in a pre-determined non-linear path without the necessity of using large transverse magnetic fields.

The foregoing and other objects of this invention will be best understood from the following description of exemplifications thereof, reference being had to the accompanying drawings, wherein:

Figs. 1, 2 and 3 are diagrams of the cross-sections of various shapes of waveguides excited in various modes to illustrate certain aspects of the invention;

2

Fig. 4 is a cross-sectional diagram taken along line 4—4 of Fig. 3;

Fig. 5 is a cross-sectional diagram similar to Fig. 4 but illustrating another aspect of the invention;

Fig. 6 is a central vertical cross-section of a microwave amplifier representing one embodiment of this invention;

Fig. 7 is a perspective view, partly broken away, of the waveguide component of Fig. 6;

Fig. 8 is a diagram illustrating certain aspects of the operation of the device shown in Fig. 6;

Fig. 9 is a cross-sectional diagram of an electron accelerator embodying this invention;

Fig. 10 is a cross-sectional diagram of a modified electron accelerator;

Fig. 11 is a cross-sectional diagram of a further modified type of electron accelerator embodying this invention; and

Fig. 12 is a perspective diagram of the electron accelerator of Fig. 11;

If, instead of confining our consideration to the linear phase velocity of a wave radiated through a waveguide, we consider certain angular paths and consider the angular phase velocities involved, we will discover that such angular velocities are within the range at which an electron can travel.

It is desired to be explained at this point what is meant herein by the expression, "the angular phase velocity of a wave in a waveguide." The angular phase velocity is the velocity at which the phase of an electromagnetic wave in a waveguide propagates along a non-linear path with respect to said waveguide, said non-linear path being so related to the longitudinal axis of said waveguide as to provide a substantially periodic angular component of motion with respect to said axis for a point moving along said non-linear path at a uniform rate.

Let us consider, first of all, a cylindrical waveguide excited in the TE_{11} mode as shown in Fig. 1. It will be seen that if we consider the direction and magnitude of the electric field around the inner circumference of the waveguide we obtain a sinusoidal variation in the field relative to the axis $a-a$. In other words, as we progress from the axis $a-a$ around the circumference of the waveguide the field increases in magnitude from zero to a maximum, back to zero, increases in the reverse direction to a maximum and then falls back to zero. If we select an arbitrary point e in the wave pattern and if we move the point so as to preserve its relation to the wave pattern as referred to a reference point such as the center c , the velocity of the

3

point would be the phase velocity of the wave. Thus, if the point e were moved along a direction at right angles to the plane of Fig. 1, the velocity would be the linear phase velocity which, as has been pointed out above, is equal to or greater than the velocity of light.

Let us now rotate the wave pattern of Fig. 1 in the direction of the dotted arrow at an angular velocity of

$$\omega = 2\pi f \quad (1)$$

where f is the frequency of the wave. This is the condition of circular polarization. If we now move the point e in the plane of Fig. 1 in the direction of the dotted arrow at an angular velocity equal to ω we find that the relation between point e and the wave pattern is preserved when related to the reference point c . In other words, the field at point e always points away from the point c , for example. Thus, the angular phase velocity of the wave in the plane of Fig. 1 is equal to ω .

If we now, in addition to its angular motion, impart to the point e a velocity v_e along the waveguide, we can derive a general expression for the angular phase velocity along any resultant path with reference to an axis passing through c . At a time $t=0$, the relationship between the phase of the angular motion of point e and the phase of the electric field of the wave will have some constant value. There is no loss of generality in assuming this initial phase difference to be zero. At a later time t and at a distance x along the waveguide from the initial point under consideration the phase ϕ_w of the wave is

$$\phi_w = \omega t - \beta x \quad (2)$$

where

$$\beta = \frac{2\pi}{\lambda_g}$$

and λ_g = the wave length of the wave in the guide. At the time t , in order for the point e to be at the same point x ,

$$x = v_e t \quad (3)$$

The phase ϕ_e of its angular motion is

$$\phi_e = \omega_e t \quad (4)$$

where ω_e is the angular velocity of the point e . In order to preserve a constant phase relation between ϕ_w and ϕ_e these values are equated as follows:

$$\omega t - \beta x = \omega_e t \quad (5)$$

but

$$x = v_e t \quad (6)$$

Therefore

$$\omega t - \beta v_e t = \omega_e t \quad (7)$$

which reduces to

$$\omega - \beta v_e = \omega_e \quad (8)$$

The well-known expression for the linear phase velocity v_p is

$$v_p = \frac{\omega}{\beta} \text{ or } \beta = \frac{\omega}{v_p} \quad (9)$$

Substituting this expression in Equation 8 and simplifying, we have

$$\frac{\omega_e}{\omega} = \left(1 - \frac{v_e}{v_p} \right) \quad (10)$$

Equation 10 is a general expression which gives the angular velocity of a point traveling along a waveguide with any given linear velocity in terms

4

of the angular velocity of the wave and the linear phase velocity of the wave, where phase equality is preserved.

Circular polarization of the wave was referred to above as an aid to a graphic visualization of the relationship involved. However, the generality of Equation 10 is not affected as the polarization becomes elliptical and reaches linear polarization. The generalization is also clearly applicable to other types of waveguides such as those of rectangular cross-section. The only special consideration that must be met is that the excitation mode which is set up in the waveguide must be such that a circular path within the wave pattern set up at any instant in the waveguide must include at least one complete alternation of the electric field as referred to any given axis or point of reference. Equation 10 represents the general condition where one such alternation of field is encountered.

As used herein, the term "reference point," as used in connection with alternations of the electric field in a circular path within the wave pattern, is intended to mean any point with respect to which an electron, considered as a negative charge, experiences a force due to the electric field present; the term "a complete alternation of the electric field" is intended to mean the presence of a single pair of such forces, one of the pair pointing toward and the other of the pair pointing away from the particular reference point under consideration.

Let us now consider a more complex wave pattern, as for example that represented by the $TE_{1,1}$ wave in a square waveguide, as shown in Fig. 2. It is clear that the circular path represented by the dotted circle in Fig. 2 includes two complete alternations of the electric field in the field pattern set up by the $TE_{1,1}$ wave when referred to the point c , since there are two pairs of forces present with respect to point c , one force of each pair pointing toward point c and the other force of each pair pointing away from point c . In other words, an electron in proceeding around the dotted circle in Fig. 2 experiences four forces with respect to point c , two of which tend to force it toward point c and the other two of which tend to force it away from point c . Since there are two complete alternations of the electric field in the field pattern of Fig. 2, referred to point c , included in the dotted circle of said figure, the angular velocity of a point e in such case need be only one-half of the velocity in the case of a single field pattern alternation in order to maintain the constant phase relation with the wave. Thus, the angular phase velocity is inversely proportional to the number of complete field alternations in a given circular path through an instantaneous wave pattern. Therefore, Equation 10 can be expressed in a still more generally applicable form

$$\frac{p \omega_e}{\omega} = \left(1 - \frac{v_e}{v_p} \right) \quad (11)$$

where p is the number of complete field alternations as described above.

If instead of selecting point c as the reference point in Fig. 2, some other point such as d were selected, only a single complete alternation of the electric field pattern would be included in the circular path referred to above, since with respect to point d there is only a single pair of oppositely-directed forces (represented by the substantially vertical field lines in Fig. 2) which would tend to move an electron toward and away from point

d. In this case, the substantially horizontal field lines are ineffective, since they would tend to move an electron only in a direction parallel to a horizontal axis passing through point *d*, and not toward or away from said point. Similarly in Fig. 1, the circular path would not encompass a complete alternation of the field pattern with respect to the point *d*, since all the forces are directed away from said point and there is therefore no pair of forces one of which pair is directed toward point *d* and the other of which pair is directed away from point *d*. With respect to point *c*, there is a single pair of forces (represented by the substantially vertical field line in Fig. 1) one of which is directed toward point *c* and the other of which is directed away from point *c*, so that with respect to this latter point the circular path includes a single complete alternation of the electric field through an instantaneous wave pattern.

Thus, in determining the value of *p* in Equation 11 the reference point or axis to which the wave pattern is referred must be kept in mind.

Although the examples cited above have involved transverse electric modes of excitation, the generality of Equation 11 also applies to longitudinal modes of excitation. Let us consider, for example, the $E_{1,2}$ mode in a rectangular waveguide, as shown in Figs. 3 and 4. In this case the point *e*, in moving through the dotted circle, includes one complete alternation of the electric field with respect to the point *c*, since with respect to this point there is a single pair of forces (represented by the substantially horizontal field lines in the upper and lower portions of Fig. 4) present, one of this pair being directed toward point *c* and the other of this pair being directed away from said point; the angular phase velocity for synchronism in this case is given directly by Equation 10, since *p* is equal to 1. The helical motion of point *e*, resulting from the circular orbital motion thereof combined with the translatory motion thereof along the waveguide at a velocity v_e , is indicated by the dotted curve in Fig. 4.

If an electron were caused to follow the path of the point *e* in each of the above instances it would persist in the particular phase relation with the wave at which it is injected into the waveguide. If the phase is such that energy is abstracted from the motion of the electron by the electric field, amplification of the wave travelling along the waveguide may be expected, whereas if the phase relation is such that energy is imparted to the electron by the electric field, the electron will be accelerated. If such acceleration is along a path which permits the electron to travel a substantial distance without being captured by the waveguide boundaries, relatively high electron velocities may be attained before the electron is intercepted by the boundaries of the guide. In some cases the acceleration may vary in direction so as to impart non-linear motion to the electron involved.

Angular velocities of a fixed and predetermined value may be imparted to electrons by magnetic fields in accordance with the known expression

$$\omega_e = \frac{eB}{10m} \quad (12)$$

where ω_e is now the electron angular velocity, *e* the electronic charge, *B* the magnetic field, and *m* the electron mass. Substituting this expression for ω_e in Equation 11 gives us a measure of the magnetic field necessary to produce a mo-

tion of the electron in synchronism with the angular phase velocity of the wave.

$$B = \frac{10\omega m}{pe} \left(1 - \frac{v_e}{v_p} \right) \quad (13)$$

If we assume *p*=1 and $v_e=0$ we obtain, in the case of 3.5 cm. wave, a value of *B* equal to approximately 3000 gauss. Equation 13 indicates that if v_e were increased, *B* could be decreased. However, for moderate values of v_e the decrease in *B* is rather small. Electrons injected into the waveguide with a voltage of about 3000 volts will permit about a ten percent reduction in the required field. The injection voltage needed to produce greater reductions in *B* rises very rapidly, especially since relativity considerations are involved.

From Equation 13 we see that if *p* is greater than 1, relatively large reductions in *B* might be obtained. Thus if *p* could be made 2, or 4, the field required would be reduced to one-half or one-quarter respectively, giving in the case of the 3.5 cm. waves fields of 1500 and 750 gauss respectively. However, if we are dealing with zero injection voltage for the electron, in considering any wave pattern to determine the number of field alternations present in the circular orbit of an electron we must not lose sight of the fact that at microwave frequencies, the diameter of the electron orbit is necessarily small, otherwise the linear velocities tangential to the direction of electron travel tend to approach the velocity of light. The increased mass resulting from such high speeds would in turn require higher magnetic fields to preserve phase synchronism. Thus in the case of the $TE_{1,1}$ mode of excitation with a 3.5 cm. wave, if we limit the tangential velocity of the electrons to one-tenth of the speed of light, the diameter of its circular orbit is about one millimeter. If *p* is increased to 2, the diameter of the electron circular orbit increases to about two millimeters at the same tangential speed. As we go to longer wavelengths (or lower frequencies) the required magnetic field decreases, thus simplifying the problem. However, shorter wavelengths (higher frequencies) require still higher fields.

In the case of an electron accelerator, we are free to choose any convenient wavelength of propagated wave. Thus with a ten centimeter wave we should obtain the desired phase coincidence, at least in the front end of the waveguide, with a field of about 1,070 gauss. Here again, an increase in *p* might be useful.

In the above discussion of the magnitude of the magnetic field, we have been assuming that the velocity of the electron along the waveguide and the mass of the electron relative to its orbital motion remained constant. Such a condition might be attained in an amplifier excited with a TE mode and with the electron injected with a tangential velocity of about 3000 volts or less. In such an arrangement energy would be abstracted from the orbital motion of the electron causing it to travel in a helix of decreasing radius but of constant pitch. Thus none of the conditions determining the value of *B* would change either across or along the waveguide. If, however, we assume an amplifier excited in an E mode and with the electron injected at a velocity along the waveguide of about 3000 volts or less, then energy will be abstracted from the linear component of the electron motion and the electron velocity along the waveguide will progressively decrease. This will require an increase of the magnetic field along the wave-

guide, as can be seen from Equation 13. In the example assumed, however, the maximum increase from the beginning of the waveguide to the end will be 11.1 per cent, this maximum being required if we assume that the electron speed reaches zero immediately ahead of the end of the waveguide.

In an electron accelerator, we are interested in feeding large amounts of energy to the electrons and this therefore will produce increases in both speed and mass which will affect the magnitude of the magnetic field. An accelerator excited in a TE mode will add energy in the orbital component of the electron path, and as the tangential velocity of the electron exceeds about 3000 volts, the electron mass will increase. From Equation 13 we see that such increase in mass will require a corresponding increase in magnetic field. To the extent that the increase of the orbital electron mass increases the mass of the electron relative to its motion along the waveguide, the velocity of the electron along the waveguide will decrease since presumably no accelerating force along the waveguide is present to compensate for such increased mass. This may likewise tend to require an increase in the magnetic field along the waveguide. However, with small or substantially zero drift along the waveguide the variation in magnetic field along the waveguide may be neglected. Under such conditions, the increase in magnetic field due to the increase in the orbital electron mass would have to be secured by a radial increase in the magnitude of the magnetic field. An advantage of such an arrangement would be the possibility of using a short air gap for the magnetic field structure, thus facilitating the production of the required magnitude of magnetic field.

If we consider an accelerator excited with an E mode such as shown in Figs. 3 and 4, the value of v_e in Equation 13 increases along the waveguide, which tends to reduce the value of B. However, as the speed of the electron exceeds that corresponding to about 3000 volts, its longitudinal mass increases, due to relativity effects. We know that there is also some increase in the transverse mass of the electron, although to a lesser degree than in the longitudinal mass. The value of m in Equation 13 is the transverse mass in this case. Such increase in the transverse mass tends to increase the value of B. No attempt is made herein to compute the net result of these effects. However, such computations could be made in order to determine what variations if any should be made in the magnetic field along the waveguide to preserve the desired phase synchronism. Since there is probably no feeding of energy into the angular momentum of the electron, it is not believed that its orbital radius will increase substantially with the increase in transverse mass.

Although in the examples above, the orbital or circular path of point e has been considered to lie in a plane perpendicular to the longitudinal axis or center line of the waveguide, the generality of Equation 11 also applies to circular paths which lie in other planes. Let us consider next the $E_{1,1}$ mode in a rectangular waveguide, with the circular path of point e lying in a plane parallel to the longitudinal center line or length of the waveguide, as shown in Fig. 5. In this case the point e in moving through the dotted circle includes one complete alternation of the electric field with respect to the point c, since with respect to this point there is a single pair of forces (represented

by the substantially horizontal field lines in Fig. 5) present, one of this pair being directed toward point c and the other of this pair being directed away from said point; the angular phase velocity for synchronism in this case is given directly by Equation 10, since p is 1.

To recapitulate, the above discussion shows that it is possible to produce a motion of electrons in a waveguide in synchronism with the angular phase velocity of the wave being radiated therethrough, and also shows that when such synchronous relation exists, a net energy interchange can take place between the electrons and the electromagnetic wave in the waveguide.

Figs. 6 and 7 illustrate a practical microwave amplifier by means of which the above principles may be put into effect. Numeral 1 generally designates an electron-discharge device according to this invention. A pair of hollow waveguide sections 2 and 3 are joined and hermetically sealed together with the longitudinal axes of the two guides at right angles to each other (see Fig. 7). The interiors of these two guides are evacuated and are in communication with each other, and in order to provide a hermetically-sealed envelope portion for the electron-discharge device, a sealing member 4 is placed in the interior of the vertically-extending waveguide 2 a substantial distance above the junction of the two guides, or on the wave-input side of the device, 25 while a sealing member 5 is placed in the interior of the horizontally-extending waveguide 3 a substantial distance to one side of the junction of the two guides, or on the wave-output side of the device.

The lower end of waveguide 2 is at the junction between the two guides, while waveguide 3 extends on both sides of said junction. The interior of waveguide 3 is sealed off from the atmosphere 40 at the side of said waveguide opposite from the wave-output side of the device, by means of a metallic end wall 3a, integral with said waveguide, which closes off the interior of the waveguide 3 and also terminates said waveguide at this side 45 of the junction between the guides 2 and 3.

As shown in Fig. 7, waveguide section 3 has an H-shaped cross-section throughout its length, while waveguide section 2 has an upper portion 2a of H-shaped cross-section and a lower portion 2b, of rectangular cross-section in its mid-section, but having transition sections above and below its mid-section. These transition sections connect the rectangular part of portion 2b to the upper H-shaped portion 2a, on the one hand, and to the H-shaped guide 3, on the other hand. Portion 2a and the lower extremity of the lower transition section of waveguide 2 have exactly the same cross-sectional dimensions as does waveguide 3, while the rectangular mid-section of portion 2b has an increased cross-sectional area relative to portion 2a and waveguide 3. The lower extremity of the lower transition section of waveguide 2 matches the cross-section of waveguide 3, is aligned with it front-to-rear in Fig. 7, 50 and is joined and sealed to it at right angles as aforesaid, the interiors of waveguides 2 and 3 being placed in communication with each other by an H-shaped aperture 6, having the same cross-section as waveguide 3 and being cut through the top wall of waveguide 3. With the 55 position of the electron-discharge device or wave amplifier 1 illustrated in Figs. 6 and 7, the longitudinal axis of guide section 2 extends substantially vertically, while the longitudinal axis of

guide section 3 extends substantially horizontally. An external magnetic structure, designated generally by numeral 7, is positioned outside of the sealed and evacuated portion of waveguide section 2, and extends downwardly somewhat below waveguide section 3, as shown in Fig. 6. Most of the magnetic structure has been removed from the device in Fig. 7, in order to show the waveguide components of said device more clearly. Structure 7 includes a pair of oppositely-disposed U-shaped permanent magnets 8 and 9, together with three vertically-aligned pole pieces 10, 11, and 12, each of which has a central opening extending therethrough. The upper legs of magnets 8 and 9 are north poles, as indicated, and the lower legs of said magnets are south poles. All of the pole pieces have the same maximum external dimensions; upper pole piece 10 is in intimate contact with the upper north poles of the magnets, and lower pole piece 12 is in intimate contact with the lower south poles of the magnets.

The upper pole piece 10 entirely surrounds upper portion 2a of waveguide 2, the hole through said pole piece being shaped accordingly, and the lower end of said pole piece is spaced slightly above the upper end of central pole piece 11 to provide an air gap 13 in the region immediately adjacent the lower end of waveguide portion 2a; pole piece 10 is tapered down to have a reduced cross-section at gap 13, to give high magnetic flux density thereat. The inner surface of pole piece 10 is in firm contact with the outer wall of portion 2a of waveguide section 2.

Central pole piece 11 surrounds portion 2b of waveguide 2, including the upper and lower transition sections which connect the rectangular part of waveguide portion 2b with the upper H-shaped waveguide portion 2a and waveguide 3, but is spaced slightly from the outer wall of portion 2b; the hole through said pole piece is shaped accordingly, so that said hole has a central region of maximum size, tapering at its upper and lower ends to upper and lower areas of decreased size. The upper face of pole piece 11 is tapered to a relatively small area which is substantially equal to that of the lower face of pole piece 10, which faces it across gap 13, while the lower face of pole piece 11 is tapered to a relatively small area substantially equal to that of its upper face. The lower face of pole piece 11 rests on, and is in firm contact with, the upper wall of waveguide section 3, and has a corresponding configuration.

A coil 14, of substantially the same length as pole piece 11, is wound around waveguide portion 2b and within pole piece 11, in the space between the outer wall of said waveguide portion and the inner wall of said pole piece, that is, in the central opening of said pole piece. Opposite ends of coil 14 are connected, by conductors 15 and 16, to opposite terminals of a source 17 of direct current, for example, a battery. The current flowing through coil 14 establishes a magnetic field within waveguide portion 2b, in a direction parallel to the longitudinal axis of said portion.

The lower face of pole piece 11 is spaced from the upper surface of pole piece 12 to provide an air gap 18 therebetween, and in this air gap is positioned the waveguide section 3. The upper face of pole piece 12 is hermetically sealed to the lower wall of waveguide section 3 and has a corresponding configuration, and, since the lower face of pole piece 11 is in firm contact with the

upper wall of waveguide section 3, said waveguide section defines the lower air gap 18.

It should be brought out at this juncture why it is preferable to use an H-shaped waveguide for waveguide section 3. It has been found that, for the same cutoff wavelength, an H-shaped waveguide can have smaller overall dimensions than a rectangular waveguide; since the dimensions of waveguide section 3 determine the length of air gap 18, this means a shorter air gap is possible with an H-shaped guide than with a rectangular guide having the same cut-off frequency. It is desirable to decrease the length of the air gaps in the magnetic circuit as much as possible, in order to decrease the total reluctance of the magnetic circuit, since rather high magnetic field strengths are necessary in devices of this character, as explained above.

The central openings through pole pieces 10, 11 and 12 all have a common longitudinal axis or center line, these pole pieces therefore being vertically aligned. Lower pole piece 12 is tapered upwardly to an area at its upper face which is smaller than the area of its lower face, but the area of its upper face is somewhat larger than the area of the lower face of pole piece 11, which faces it across gap 18, for a purpose to be explained hereinafter.

A circular aperture 19 is cut through the central portion of the lower wall of waveguide section 3, said aperture having its center aligned with the longitudinal axes or center lines of the openings in pole pieces 10, 11 and 12. The upper end of the central opening in pole piece 12 has the same diameter as aperture 19, and from this end said central opening is enlarged as we progress downwardly, by an outward taper, to a diameter approximately equal to that of the central portion of the central hole in pole piece 11. When this diameter of the hole in pole piece 12 has been reached, it is maintained constant from the point where it is reached, downwardly to the lower end of said pole piece.

A hollow metallic cylinder 20 is hermetically sealed into the lower end of the central opening in pole piece 12, and projects downwardly therefrom below the lower end of said pole piece. A sealing member or disc 21 closes and hermetically seals the lower open end of cylinder 20. From the above-described structure, it may be seen that a hermetically-sealed enclosure is provided, constituted by the following elements: disk 21, cylinder 20, pole piece 12, waveguide 3 with sealing member 5 and end wall 3a, and waveguide 2 with sealing member 4. This enclosure is evacuated and hermetically sealed to provide an evacuated envelope.

A coil 22 is wound within pole piece 12, in the central opening thereof, this coil having a length such that it extends from the lower external wall of waveguide section 3 to a point adjacent the upper end of cylinder 20. Opposite ends of coil 22 are connected, by conductors 23 and 24 sealed through disk 21, to opposite terminals of source 17; current flowing through coil 22 establishes a magnetic field within pole piece 12, in a direction parallel to the longitudinal axis of the central opening thereof. Conductors 23 and 24 are sealed through disk 21.

An electron gun and injection structure, designated generally by the numeral 25, is positioned and mounted within the central opening in pole piece 12, in a location an appreciable distance below aperture 19. Electron gun structure 25 comprises a central electron-emissive cathode

11

element 26, a concentric hollow open-ended cylindrical primary anode element 27 radially spaced from element 26, and a coaxial deflecting or secondary ring anode element 28 which is spaced beyond (above) the upper ends of the elements 26 and 27. Cathode 26 is provided with an electron-emissive coating of any suitable type, this coating being heated to the temperature of thermionic emission by a suitable heater (not shown), the opposite ends of which are connected, by means of leads 29 and 30, to opposite ends of the secondary winding 31 of a heater transformer 32, the primary winding of which is connected to a suitable source of heating current. The coaxial line 33, which supports the cathode element 26, passes out of the evacuated interior of the device through disk 21 and is sealed therethrough, the inner conductor of this line being hermetically sealed into the outer conductor thereof by means of a vitreous seal 34.

Lead 30, which is connected to the outer conductor of coaxial line 33, is electrically connected to the negative end of a direct current source 35 of high voltage, so as to maintain cathode 26 at a suitable negative potential. Anode element 27 is connected, by a conductor 36 which is sealed through disk 21, to the positive terminal of source 35, so as to maintain said anode at a high positive potential with respect to cathode 26. Conductor 36 also supports element 27 in position.

A lead-in and support wire 37, which is sealed through disk 21, connects ring anode 28 to an intermediate point, on source 35, which is positive with respect to cathode 26.

Finally, to complete the electrical connections to the device 1, a conductor 38 electrically connects cylinder 20 to an intermediate point, on source 35, which is positive with respect to cathode 26 and is nearer the positive end of source 35 than is the point to which ring anode 28 is connected. Since metallic cylinder 20 is fastened to pole piece 12, since said pole piece is fastened to waveguide section 3, and since waveguide section 3 is fastened to waveguide section 2, all of these fastenings being hermetic seals, a potential positive with respect to cathode 26 is applied to waveguide section 2.

The output end of waveguide section 3 may be brought out in another plane than that of Fig. 6, in order to clear magnet 8; the showing of said output end and said magnet in the same plane, in Fig. 6, is merely for convenience of illustration.

The magnetic circuit including the permanent magnets may be traced as follows: from the north pole of either magnet 8 or 9, through pole piece 10, gap 13, pole piece 11, gap 18, and pole piece 12, to the south pole of the same permanent magnet. It will be seen that magnetic flux substantially parallel to the longitudinal axis of waveguide 2 is provided across gaps 13 and 18 mainly by this permanent magnet circuit, while magnetic flux substantially parallel to the said longitudinal axis, between gaps 13 and 18, is provided mainly by coil 14, and magnetic flux substantially parallel to said longitudinal axis, below gap 18, is provided mainly by coil 22.

Having described the structure of the electron-discharge device 1, we will now proceed to a consideration of the mode of operation thereof as a microwave amplifier.

A copious supply of electrons is thermionically emitted from cathode 26, these electrons originally proceeding toward primary anode 27 because of the positive bias thereon. As described above, coil 22 produces a longitudinal magnetic

12

field along the axis of the central opening in pole piece 12. Due to the transverse motion (from cathode 26 toward anode 27) of each electron across this magnetic field, each electron is caused to move in an orbital substantially circular path around the longitudinal axis of the opening through lower pole piece 12.

The above discussion has neglected the effect of ring anode 28. However, due to the presence of this element which is biased positively with respect to cathode 26, each electron is caused to move or drift upwardly axially along the opening in pole piece 12 with a velocity v_e determined by the potential on anode 28. Each electron, as a result of its circular orbital motion combined with its longitudinal motion, follows a helical path; all of the electrons taken together can be pictured as a hollow substantially cylindrical cloud which rotates and moves upwardly along the longitudinal axis or center line of pole piece 12. This cloud can move beyond or above element 28 because said element is toroidal, having a hole in its center.

Now referring to Fig. 8, this figure represents a TE_{01} mode wave radiating or propagating through the TE_{01} wave amplifier of this invention, this wave propagating downwardly along waveguide 2 in the direction of arrow A, turning the right angle at the junction of guides 2 and 3, then propagating along waveguide 3 in the direction of arrow B. Termination or end wall 3a of waveguide 3 is constructed and arranged to terminate said waveguide at this closed end in its characteristic impedance, thereby preventing any appreciable reflection of waves from this end of said guide; this termination is represented as a resistance in Fig. 8.

The arrows extending between the walls of the waveguides 2 and 3 in Fig. 8 represent the electric field lines for an instantaneous wave pattern. It will be noted that, at this instant, right at the junction between guides 2 and 3, as indicated by arrows C and D, respectively, the electric force has a maximum value downward at an angle at the left side of aperture 19, and a maximum value upward at an angle at the right side of said aperture.

Now considering the changes in the wave pattern with respect to time which take place along any particular line, such as line D, there is a sinusoidal variation of the electric field along this line at a periodicity corresponding to the linear phase velocity of the electromagnetic wave. In other words, the angular position or location of line D does not change with respect to time, but the force represented by said line varies only from a maximum to zero and then to a maximum in a direction directly opposite to that indicated by the arrow on said line in Fig. 8; all of these changes occur along the line D.

As the rotating cloud of electrons, which is drifting upwardly axially of pole piece 12, reaches the vicinity of aperture 19, it reaches a region of increased longitudinal magnetic field strength. The aforesaid cloud passes through aperture 19 and proceeds toward aperture 6 at the upper side of waveguide 3. In the vicinity of aperture 6, at the upper end of gap 18, the value of the magnetic field strength B is sufficient, due to the presence of pole pieces 11 and 12 on opposite sides of this gap (the lower surface of pole piece 11 having a relatively small area), to satisfy Equation 13, so that in this region the electrons are moving in synchronism with the angular phase velocity of the wave. This region, in the vicinity

of aperture 6, may therefore be termed a synchronous field region. Due to the somewhat larger area of the upper face of pole piece 12, in the lower part of waveguide 3 (that is, in the vicinity of aperture 19), the value of the magnetic field strength B is somewhat less than that necessary to produce electron motion in synchronism with the angular phase velocity of the wave; in other words, the electron angular velocity is less in the vicinity of aperture 19 than in the vicinity of aperture 6 (see Equation 12).

Due to the fact that the cloud of electrons originally is a complete circle, there would be just as many electrons abstracting energy from the wave at any instant on one side of the circle as there would be imparting energy thereto on the other, because on one side of the center of the waveguide there would be forces tending to decrease the orbital radius of the electrons, while on the other side of the center there would be equal and opposite forces tending to increase the orbital radius of the electrons. Therefore, in order to change the net energy level of the wave, it is necessary to select the electrons having only a particular phase with respect to the wave, and to cause only these electrons to react with the wave. The aforesaid selection is made by an action which may be termed "angular bunching" of the electrons.

Consider now a circular cloud of electrons which arrives in the vicinity of aperture 6 (that is, in the synchronous field region) at an instant when the electromagnetic wave in the waveguide has the wave pattern represented in Fig. 8. At this instant, the forces C and D have their maximum values in the directions indicated by the respective arrows thereon. The right-hand half of the aforesaid circular cloud of electrons is pushed upwardly by force D, while the left-hand half of said cloud is pushed downwardly by force C.

When the upwardly-pushed half of the circular cloud has rotated so that it is on the left-hand side, forces C and D have reversed in direction, since in this region the electrons are moving in synchronism with the angular phase velocity of the wave. At this time, therefore, force C is directed upwardly, and force D is directed downwardly. The upwardly-pushed half of the circle is therefore now given another upward push, while the downwardly-pushed or opposite half of the circle is given another downward push. This process repeats itself as the electrons continue to rotate, so that the half of the circle of electrons which has a certain predetermined phase with respect to the wave is given repeated upward pushes, while the opposite half is given repeated downward pushes. As a result, substantially half of the circle of electrons proceeds upwardly into waveguide portion 2b, the other half of the circle proceeding downwardly toward the somewhat weaker magnetic field region in the vicinity of aperture 19.

The end result of the above action may be likened to splitting a hollow cylinder lengthwise along its longitudinal axis and displacing one half axially downward and the opposite half axially upward. The half of the cylindrical cloud of electrons thus selected or "bunched" and pushed upwardly into waveguide portion 2b may be thought of as substantially half of a hollow cylinder which is rotating and drifting upwardly.

The half of the circle of electrons which does not have the desired predetermined phase with respect to the wave is pushed downwardly, as

above described, into the region of somewhat weaker longitudinal magnetic field in the vicinity of aperture 19. In this region, the angular velocity of the electrons is decreased (see Equation 12), so that these electrons lag behind the angular phase velocity of the wave. Eventually the lag becomes equal to one complete cycle of the wave, and at such a time these electrons have the certain desired predetermined phase with respect to the wave, so that these electrons are pushed upwardly into waveguide portion 2b to be effective for purposes of amplifying the traveling wave, as described hereinafter.

If desired, the potential on element 28 may be made such that the downward push of the electrons of improper phase, by the wave, will be insufficient to force such electrons clear down to the lower wall of waveguide 3, there to become trapped because of the positive potential of said wall.

The above-described events which take place in gap 18 may be termed the process of angular bunching, since only a semi-cylindrical group or bunch of electrons having a certain predetermined phase with respect to the wave travels upwardly into waveguide portion 2b.

The angularly-bunched electrons move upwardly from the vicinity of aperture 6 into waveguide portion 2b. Because these electrons are moving out of the high-flux-density gap 18 into a region of lesser magnetic flux density, the angular velocity of the electrons will decrease, in accordance with Equation 12, and the motion of the electrons will no longer be in phase synchronism with the angular phase velocity of the wave. However, these bunched electrons will maintain the same positions relative to each other, because the angular velocities of all of such electrons will be simultaneously decreased by the same amount.

Because the electrons in this region are not moving in synchronism with the angular phase velocity of the wave, there is a substantially zero net energy interchange or reaction between the electrons and the electromagnetic wave in said region.

The magnetic field B in the upper air gap 13, due to the presence of pole pieces 10 and 11 with their reduced cross-sections facing each other across this gap, is sufficient to satisfy Equation 13, so that the region of this air gap may also be termed a synchronous field region.

The tangential velocity of the electrons is held fixed. The interior of waveguide portion 2b may be termed a drift space, and in this space the angular velocity of the electrons decreases, as explained above. Since the tangential electron velocity is held fixed, and since the angular velocity of the electrons decreases, the diameter of the circular electron orbit must necessarily increase. To allow for this increase in orbital diameter, the waveguide portion 2b has an increased cross-section, as previously described.

In order for the rotating upwardly-drifting half-cylindrical angularly-bunched cloud of electrons to give up energy to the wave in the waveguide, it is necessary that such electrons have a predetermined appropriate phase with respect to the wave in the synchronous field region 13. Waveguide portion 2b may have any convenient length, and in order to achieve the necessary and appropriate phase relation of the electrons and the wave, waveguide 2 may be given a twist around its longitudinal axis. The aforesaid phase relation may be varied by vary-

ing either the length of waveguide portion 2b or the twist of waveguide 2 between aperture 6 and gap 13. Since the wave pattern is in effect rotated by twists in the waveguide (that is, it follows twists in the waveguide), while the electron path is unaffected by twists in the guide, the phase relation of the wave and the electrons can be varied by twisting the guide. It should be apparent that the said phase relation can be varied also by varying the length of waveguide portion 2b, since the length of said guide determines the number of circular orbits traveled by the electrons, for a given velocity along the guide and for a given electron angular velocity.

The angularly-bunched or half-cylindrical cloud of electrons drifts upwardly along waveguide portion 2b, the angular velocity of the electrons first decreasing as they proceed upwardly from aperture 6, due to the decreasing longitudinal magnetic field, and then gradually increasing as the electrons approach gap 13, due to the increasing longitudinal magnetic field.

As the electrons enter the synchronous field region at gap 13, their angular velocity increases sufficiently so that the motion of the electrons is in synchronism with the angular phase velocity of the wave. Under these conditions, and since at this position the angularly-bunched electrons have the proper phase relation to the wave to impart energy thereto, energy is abstracted from the orbital motion of the electrons by the electric field of the wave, resulting in an increase in the energy level of the wave and a decrease in the orbital radius of travel of the electrons. This increase in energy level of the microwaves traveling along the waveguide is, of course, amplification of the microwaves.

Since the angular-bunching action selects and causes to react with the wave only those electrons which have the proper phase relation with the wave to impart energy thereto, there is a net increase in the energy level, or an amplification, of the wave.

The synchronous field region extends substantially throughout gap 13, so that the motion of the electrons is in synchronism with the angular phase velocity of the wave substantially throughout this gap; therefore, during substantially the entire travel of the electrons through this gap, they impart or give up energy to the traveling wave. Electrons at the upper end of gap 13, or therebeyond, have given up substantially all of their available orbital energy, and such electrons are traveling substantially axially of pole piece 10; these electrons eventually wander to the walls of waveguide 2, which are supplied with a positive potential by lead 32, and return to the cathode.

To summarize, the microwave amplifier of this invention functions as follows: the electromagnetic wave produces angular bunching of the electrons in the region 18, the bunched electrons then traveling upwardly and giving up energy to the electromagnetic wave in the region 13.

Now referring to Fig. 9, this figure shows an electron accelerator according to this invention. A waveguide 39 is hermetically sealed and evacuated to provide an envelope for the electrons to be accelerated. One end of said guide is closed by an end wall 39a, on the interior surface of which is mounted a suitable target 40. Two concentric lines 41 and 42 have inner conductors 43 and 44, respectively, which extend into waveguide 39 through suitable apertures provided in the end wall of said guide opposite from wall 39a. Con-

ductors 43 and 44 are so arranged and positioned with respect to guide 39, and are so supplied with microwave energy, that they act as exciting rods to establish an $E_{1,2}$ mode wave in said guide. The field pattern of this mode of wave is shown in Figs. 3 and 4. The guide 39 is evacuated and a vitreous sealing member 45 seals off from the atmosphere the opening in guide 39 through which conductor 43 extends, while a similar sealing member 46 seals off the opening through which conductor 44 extends.

An electron-emissive cathode element 47 is positioned centrally of guide 39 near the wave-input end thereof, this element being supported in position by means of a pair of lead-in conductors 48 and 49 which are sealed through the side wall of said guide. A hollow open-ended cylindrical primary anode element 50 is positioned in guide 39 concentrically of cathode 47, element 50 being spaced from cathode 47 and being supported in position by a lead-in conductor 51 sealed through the side wall of said guide. A coaxial deflecting or secondary ring anode element 52 is positioned in guide 39 on the side of cathode 47 toward target 40, element 52 being supported in position in said guide by a lead-in conductor 53 sealed through the side wall of said guide.

A coil 54 is wound around the waveguide 39, adjacent turns of said coil being spaced further and further apart as it progresses from cathode 47 toward target 40. This coil has a length substantially equal to that portion of the length of the guide, from the end of cathode 47 closest to the wave-input end of the guide, to wall 39a.

The connections from the various elements of the Fig. 9 accelerator to the external voltage sources are similar to those of Fig. 6; that is, cathode 47 is connected in the same manner as cathode 26, anode 50 is connected in the same manner as anode 27, anode 52 is connected in the same manner as anode 28, coil 54 is connected in the same manner as coils 14 or 22, and waveguide 39 is connected by lead 55 in the same manner as waveguides 2 and 3.

By the above-described connections, a longitudinal magnetic field is established by coil 54 along the axis or center line of guide 39, and, when the electron gun and injection structure 47-50-52 and the coil 54 are energized, a hollow substantially cylindrical rotating cloud of electrons, moving to the right along waveguide 39 with an initial velocity v_e , is produced, the action in this respect being substantially similar to the action of the electron gun and injection structure of Fig. 6.

It is desired to be made clear at this point that there is a difference between the action of an amplifier of this invention and the action of an electron accelerator according to this invention. In the wave amplifier, in order to increase the energy level of the wave, it is necessary to bunch the electrons, in order to select and to cause to react with the wave only those electrons which have a particular phase with respect to the wave, since otherwise at any instant there would be just as many electrons abstracting energy from the wave as would be imparting energy thereto at the same instant. In the electron accelerator, on the other hand, it is not considered necessary to bunch or select only particular electrons. Although some of the electrons will impart energy to the wave, thereby being decelerated, others will abstract energy therefrom and will be accelerated as desired; it is immaterial whether the net energy level of the wave is changed or not, and

electrons are ordinarily present in sufficient numbers so that it is entirely satisfactory to accelerate only some but not all of them, the number of those accelerated being ample to accomplish the desired end result, whatever that may be.

The magnetic field strength B in the vicinity of anode 52, resulting from the energization of coil 14, and the initial velocity v_e along waveguide 39, resulting from the injection voltage between cathode 47 and anode 52, are both such as to satisfy Equation 13, so that in the vicinity of anode 52, the helical motion of each electron is in synchronism with the angular phase velocity of the E mode wave propagating, radiating, or travelling along guide 39 from the left-hand end toward the right-hand end thereof. Since the electrons are moving in synchronism with the angular phase velocity of the wave, in the vicinity of anode 52, there will be an interchange of energy between the electrons and the electromagnetic wave radiating through waveguide 39, substantially half of the electrons abstracting energy from the electric field or wave and substantially half of the electrons giving up or imparting energy to the electric field or wave. Because of the E mode excitation of the waveguide, those electrons, of the hollow cylindrical rotating cloud, which abstract energy from the wave, are given a push along the longitudinal axis of the waveguide, in the direction of target 40. In other words, they are accelerated along the guide, thereby increasing their velocity v_e .

As the velocity v_e increases, the quantity inside the parentheses in Equation 13 decreases, so that the magnetic field B necessary to maintain the electrons in motion in synchronism with the angular phase velocity of the wave decreases. Therefore, as we progress along the guide from anode 52 to target 40, the spacing between adjacent turns of coil 54 is increased to decrease B , corresponding to the increase of v_e , in such a manner as to maintain synchronism between the motion of the electrons and the angular phase velocity of the wave, throughout substantially the entire travel of the electrons from anode 52 to target 40. Those electrons which are injected into the waveguide with such a phase relation to the wave as to abstract or absorb energy therefrom, are therefore accelerated throughout substantially their entire travel, from the vicinity of anode 52 to the target end of waveguide 39, so that they strike target 40 with a very high velocity, thus producing high voltage X-rays, for example, if said target is made of an appropriate material. Such electrons can return to the cathode by means of lead 55.

The electrons which are injected into the waveguide with such a phase relative to the wave as to give up energy thereto, are thereby decelerated and subsequently either drop into phase with subsequently-emitted electrons being accelerated or wander to the side wall of the waveguide and return to the cathode. In either case, they do not interfere appreciably with the accelerated electrons, and the device of Fig. 9 therefore functions very effectively and simply as an electron accelerator, with the waveguide thereof excited with an E mode wave.

The interior of waveguide 39 is hermetically sealed off from the atmosphere and evacuated, in accordance with conventional electron-discharge device practice.

It has been disclosed above, in the general discussion of the theory on which this invention is based, that an electron accelerator excited in a

TE mode will add energy in the orbital component of the electron path, and as the tangential velocity of the electron exceeds about 3,000 volts, the electron mass will increase. With small or substantially zero drift along the waveguide, the increase in magnetic field required by Equation 13 due to the increase in the orbital electron mass, will have to be secured by a radial increase in the magnitude of the magnetic field.

Fig. 10 illustrates an electron accelerator which operates in accordance with the principles just stated. A hollow waveguide 56 is closed at both ends and has, near the lower end wall 56a thereof, an exciting rod 57 extending into the interior of said guide through a suitable opening in the side wall thereof. Rod 57 is sealed through the side wall of said guide, and is adapted to be connected to a source of microwave energy to establish or set up a TE_{0,1} mode wave in said guide. The end of waveguide 56 opposite from end wall 56a is closed, and said waveguide is terminated at this end by a wave impedance means 58 which functions to prevent any appreciable reflection of microwave energy from this end of the waveguide.

Upper and lower pole pieces 59 and 60, respectively, surround waveguide 56 in the vicinity of impedance means 58, said pole pieces being axially aligned with each other and being vertically spaced from each other to provide a short air gap 61. Pole pieces 59 and 60 are coupled to a source of magnetomotive force (not shown), which may be a permanent magnet for example, in such a manner that there is longitudinal magnetic flux in gap 61. Pole pieces 59 and 60 are each tapered toward gap 61 so that the surfaces which face each other across said gap have rather small cross-sections, thus producing a very high flux density at said gap.

Lower pole piece 60 has a central hole extending entirely therethrough to accommodate therein waveguide 56. Upper pole piece 59, which surrounds waveguide 56 adjacent the upper end thereof, is solid above the end of said guide, but has a central aperture 63 extending upwardly from the lower end thereof a short distance thereto into to accommodate therein the upper end portion of guide 56; above this a pyramidal opening 62, the lower end of which merges into the walls defining aperture 63, extends upwardly into pole piece 59 a short distance. As a result of the above-described pole piece configuration, a substantially longitudinal magnetic field is provided inside guide 56, this field being weakest at the center of said guide and increasing in strength as one progresses radially outwardly from the center of said guide; this field is strongest at the side wall of said guide.

It is to be understood that waveguide 56 is entirely closed and hermetically sealed from the atmosphere, so that the interior thereof can be evacuated.

An electron-emissive cathode element 64 is mounted centrally inside waveguide 56 in a plane immediately below the lower end of gap 61; said element is supported in position by the lead-in conductors 65 and 66 which are sealed through the side wall of guide 56. A hollow open-ended cylindrical primary anode element 67 is mounted in guide 56 concentrically of cathode 64, element 67 being radially spaced from said cathode and being supported in position by a lead-in conductor 68 sealed through the side wall of said guide. A grid structure 69, of such size as to cover substantially all of the interior hollow

space inside guide 56, is mounted horizontally inside said guide, in a plane immediately above the upper end of gap 61; this grid is supported in position by a lead-in conductor 70 which is sealed through the side wall of said guide.

Leads 65, 66, and 68 are connected to suitable direct current sources (not shown) in such a manner that anode 67 has a positive potential with respect to the electron-emitting cathode 64. Conductor 70 is connected to a source in such a way that grid 69 is positive with respect to cathode 64.

Electrons emitted from cathode 64 proceed toward anode 67 because of the positive bias thereon. These electrons are made to travel in circular orbits as a result of their transverse motion across the longitudinal magnetic field established by the substantially vertical leakage flux between pole pieces 59 and 60. The electrons thus traveling in circular orbits are caused to have a small upward drift or velocity along guide 56 by a small positive bias applied to grid 69. This grid also has another function which will be described hereinafter. The magnetic field strength B in the central portion of gap 61 is sufficient to satisfy Equation 13, so that the motion of the rotating hollow cylindrical slowly-drifting cloud of electrons is originally in synchronism with the angular phase velocity of the H wave radiating upwardly along waveguide 56. Since this condition of angular phase synchronism exists, there will be an interchange of energy between the electrons and the electromagnetic wave radiating through waveguide 56, substantially half of the cloud of electrons abstracting energy from the electric field or wave and substantially half of the cloud giving up or imparting energy to the electric field or wave. Because of the H mode excitation of the guide, those electrons of the hollow cylindrical rotating cloud which abstract energy from the wave, are given a push toward the side wall of the guide, so that in effect their orbital radius is increased and they begin to travel in larger orbits. Energy is added, therefore, in the orbital component of the electron path, and the tangential velocity of such electrons increases, since their angular velocity ω_e remains constant.

Each line of magnetic flux from pole piece 59 to pole piece 60 is directed downwardly and also radially outwardly, due to the aperture 62 in pole piece 59 and to the annular shape of pole piece 60. As some of the electrons begin to travel in larger orbits, the path of the same is substantially a spiral, since the electron upward drift is small. The magnetic flux lines tend to exert a "guiding" action on such electrons, so that, in the absence of any positive bias on grid 69, such electrons would tend to "slide" downwardly along the flux lines as their orbital radius increases, since the flux lines are directed downwardly as they progress radially outwardly. However, grid 69 is given a sufficient positive bias to counteract this tendency toward downward motion of the accelerated electrons; this bias is, in fact, slightly greater than that necessary to counteract the downward-motion tendency, so that the electrons have a net small upward drift or velocity along guide 56.

As the orbital radius of those electrons which have the proper phase is increased due to the addition of energy in the orbital component of the electron path, the tangential velocity of such electrons increases, since their angular velocity ω_e remains constant. Below values of electron

tangential velocity at which the orbital electron mass begins to increase due to relativity effects, the magnetic field B between pole pieces 59 and 60 is constant and the electron angular velocity ω_e is constant, so that the electron motion stays in synchronism with the angular phase velocity of the wave propagating along guide 56. However, as the tangential velocity of the accelerated electrons exceeds about 3,000 volts, the electron mass will increase. From Equation 13, it may be seen that this increase in orbital electron mass m requires an increase in magnetic field B in order to maintain the electron motion in synchronism with the angular phase velocity of the wave. Since in Fig. 10 the tangential velocity of the accelerated electrons increases as their orbital radius increases, the orbital electron mass increases as the orbital radius increases, so that the required increase in magnetic field has to be secured by a radial increase in the magnitude of the magnetic field; as described above, the configuration of pole pieces 59 and 60 is such that there is a radial increase in the strength of the magnetic field, as required to maintain the motion of the accelerated electrons in synchronism with the angular phase velocity.

From the above description, it may be seen that a very effective electron accelerator has been devised according to the invention, the energy necessary to accelerate the electrons being provided by a TE mode wave in a waveguide.

Let us now consider a waveguide which, instead of being straight, has imparted thereto some curvature. This enables us to devise arrangements for imparting curved paths to the electron under the influence of the field pattern. In Fig. 2, let us adopt the reference point d and establish the conditions of angular phase synchronism. Thus, p reduces to 1, and from Equation 11 we see that with v_e equal to zero the angular frequency of the electron equals the angular frequency of the wave. Thus, when the electron is at the top of the waveguide it will be pushed up. When it reaches the left side of the waveguide, the voltage of the wave will be zero and there will be no sidewise push. However, in traveling through this quadrant there will also be a component of force pushing the electron to the right. When the electron reaches the bottom of the guide, it will again be pushed up, while in traveling through the proceeding quadrant it will be pushed to the left. As we progress around the waveguide we find that the push on the electron is always up and alternately to the right and left under conditions of synchronism, resulting in a net push upward. If the electron is traveling at a given velocity at right angles to the wave pattern of Fig. 2, the resultant forces on the electron will cause it to move substantially in a circle, which it will do provided we bend the waveguide in a circle of the proper radius. Such an arrangement might be useful in devices where it is desired to cause an electron traveling at high speed to travel in a circle, the field pattern in such cases supplying the centripetal force.

Now let us consider a special case of the analysis of the angular phase velocity of a wave in a waveguide, the principles of which are applicable to a microwave amplifier, as well as to an electron accelerator.

Consider a waveguide with an excitation in which the field pattern has at least one complete reversal along a closed path transverse to the waveguide, such as that shown in Figs. 3 and 4, for example. If an electron is injected into this

guide in such a way that it travels along substantially a straight line, the electron will travel along in phase with the phase velocity of the wave if the waveguide, which should be non-circular, is twisted along its length at the proper pitch. Let us designate as g the length along which the waveguide is given a complete half turn relative to the path of the electron. When the electron has traveled through the distance g the wave should have propagated beyond the position of the electron by an amount equal to $\lambda/2$ so that the reversal due to the twist of the waveguide will orient the field to maintain the same phase relation with respect to the electron as at the zero point of distance d . If v_p is the phase velocity of the wave, v_e is the velocity of the electron along the guide and λ_g is the wavelength in the waveguide, then we can calculate the time t during which the wave has progressed $\lambda g/2$ with respect to the electron as

$$t = \frac{\lambda_g}{2(v_p - v_e)} \quad (14)$$

But

$$g = v_e t \quad (15)$$

Substituting the value of t from Equation 14,

$$g = \frac{v_e \lambda_g}{2(v_p - v_e)} \quad (16)$$

If we wish to produce an electron accelerator we can excite a rectangular waveguide with a longitudinal electric mode of the necessary configuration to give at least one reversal of the field pattern, as pointed out above, and to produce acceleration of the electron along the guide. With a given velocity of electron injection, we can calculate the pitch of the waveguide twist at the point of injection, from Equation 16. However, the electrons of proper phase will start to accelerate, thus reducing the pitch progressively along the guide. Thus, even with moderate injection speeds, due to the relatively large accelerating voltages which can be produced in waveguides, the pitch of the twist, even within the initial length of waveguide, can be made reasonably small. The magnitude and variation in pitch can be calculated from the characteristics of the waveguide as related to the frequency of the wave, as well as the voltages within the waveguide. We can designate the pitch of the waveguide in terms of turns per λ_g as

$$h = \frac{v_p - v_e}{v_e} \quad (17)$$

If v_e increases by an increment v_i per unit length then the pitch at a point a distance L along the waveguide from the point of injection is given as

$$h = \frac{v_p - (v_e + v_i L)}{v_e + v_i L} \quad (18)$$

A moderate longitudinal magnetic field may be utilized to align the electron flow along the waveguide, to thereby prevent wandering of the electrons transversely.

If, for example, a voltage of 500,000 volts per wavelength is set up in the waveguide with a ten centimeter wave, 1,000,000,000 volts would be imparted to the electron in a distance of 20,000 centimeters.

If the electron is caused to travel in a circular or orbital path by the imposition of a magnetic field and a transverse component of velocity of

the electron relative thereto, the pitch of the twist in the waveguide can be reduced if the electron is traveling in a sense opposite to that of the waveguide twist. If we give to the electron an orbital period ω_e in opposition to the twist in the waveguide, then we can multiply the distance G by a factor k where

$$k = \frac{\omega}{\omega - \omega_e} \quad (19)$$

or

$$G = \frac{\omega}{\omega - \omega_e} \times \frac{v_e \lambda_g}{v_p - v_e} \quad (20)$$

where $G = 2g$.

Now referring to Figs. 11 and 12, these figures illustrate an electron accelerator according to this invention, this accelerator utilizing some of the twisted waveguide principles above set forth. Fig. 11 is a longitudinal cross section through the electron accelerator, while Fig. 12 is a perspective diagram of the waveguide itself. Waveguide 71, which may have a rectangular cross section as shown, is hermetically sealed and evacuated to serve as an envelope for the electrons to be accelerated. One end of the guide is closed by an end wall 71a, on the interior surface of which is mounted a suitable target 72 on which the accelerated electrons may impinge with a high velocity. Two concentric lines 73 and 74 have inner conductors 75 and 76, respectively, which extend into waveguide 71 through suitable apertures provided in the end wall of said guide opposite from wall 71a. Conductors 75 and 76 are so arranged and positioned with respect to guide 71, and are so supplied with microwave energy, that they act as exciting rods or probes to establish an $E_{1,2}$ mode wave in said guide. The field pattern of this mode of wave is shown in Figs. 3 and 4. Conductors 75 and 76 are sealed through the end wall of guide 71 into the evacuated interior thereof.

An electron-emissive cathode element 77 is positioned eccentrically in guide 71 near the wave-input end thereof, this element being supported in position by means of a pair of lead-in conductors 78 which are sealed through the side wall of said guide. A ring anode element 79 is positioned in guide 71 adjacent to and aligned with cathode 77, on the side of cathode 77 toward target 72, element 79 being supported in position in said guide by a lead-in conductor 80 sealed through the side wall of said guide.

55 A coil 81 is wound around the waveguide 71, this coil having a length substantially equal to that portion of said guide from cathode 77 to wall 71a.

Cathode leads 78 are connected to a source 60 (not shown) in such a manner as to heat said cathode to the temperature of thermionic emission and as to apply a negative potential to said cathode. Anode lead 80 is connected to the same source as is cathode 77, in such a manner as to make the anode 79 positive with respect to cathode 77. Leads 82 and 83, connected to opposite ends of coil 81, are connected to a suitable source, to energize said coil so that the same supplies a moderate substantially uniform longitudinal magnetic field inside guide 71.

Electrons emitted from cathode 77 are attracted toward anode 79 because of the positive potential thereon, and travel along substantially a straight line from cathode 77 to target 72. 75 This line is eccentric with respect to the longi-

tudinal axis of the waveguide, due to the eccentric position of cathode 77. The moderate longitudinal magnetic field provided by coil 81 is utilized to align the electron flow along a line parallel to the longitudinal axis of guide 71, thereby to prevent wandering of the electrons transversely.

As represented in Fig. 12, waveguide 71 is twisted along its length at a certain pitch; the length along which the waveguide is given a complete half turn relative to the path of the electron, which path is indicated by the dotted line F in Fig. 12 and is substantially a straight line, is denoted by g. The line or path F, although substantially linear with respect to space, is non-linear with respect to waveguide 71, since said guide is twisted along its length. The length g, at the point of injection of the electrons, has the proper value determined by Equation 16 for the electron injection voltage used, so that the electrons travel along the waveguide 71 in phase with the phase velocity of the wave.

Since the electrons are moving in synchronism with the angular phase velocity of the E mode wave, there will be an interchange of energy between the electrons and the electromagnetic wave radiating through waveguide 71, those electrons having the proper phase abstracting energy from the electric field or wave and thereby being accelerated. Because of the E mode excitation of the waveguide, those electrons which abstract or absorb energy from the wave are given a push along the longitudinal axis of the waveguide, in the direction of target 72. In other words, they are accelerated along the guide, thereby increasing their velocity v_e . The increase of velocity v_e will increase the length g, as seen from Equation 16, so that the twist of the waveguide may be reduced progressively along the guide. The variation in waveguide pitch along the guide may be calculated from Equation 18, and guide 71 is designed in accordance with this equation.

Therefore, the travel or motion of the electrons, along the guide 71, is maintained in synchronism or in phase with the angular phase velocity of the wave, throughout substantially the entire travel of the electrons from anode 79 to target 72. Those electrons which are injected into the waveguide with such a phase relation to the wave as to abstract or absorb energy therefrom (here termed with the proper phase), are therefore accelerated or given a longitudinal push throughout substantially their entire travel, from the vicinity of anode 79 to the target end of guide 71, so that they strike target 72 with a very high velocity. Because of the eccentricity of path F with respect to the longitudinal axis of the waveguide, these electrons are given a longitudinal push in the same direction throughout substantially their entire travel. Such electrons can return to the cathode from target 72 by means of lead 84, which is connected to waveguide 71 and to the source to which cathode 77 is also connected.

As should be apparent from the above description, the device of Figs. 11 and 12 functions very effectively as an electron accelerator, with the waveguide thereof excited with an E or longitudinal electric mode wave.

Of course, it is to be understood that this invention is not limited to the particular details as described above, as many equivalents will suggest themselves to those skilled in the art. It is accordingly desired that the appended claims be given a broad interpretation commensurate with the scope of this invention within the art.

What is claimed is:

1. In combination: a wave guide structure adapted to be excited by electromagnetic energy having a predetermined angular phase velocity; a source of electrons; means, adjacent said source of electrons, for injecting electrons from said source into said wave guide structure with an orbital component of motion; and means, adjacent said wave guide structure, for adjusting the angular velocity of said orbital component of motion of said electrons to substantially equal the angular phase velocity of said electromagnetic energy.

2. In combination: a wave guide structure adapted to be excited by electromagnetic energy having a predetermined angular phase velocity; a source of electrons; means, adjacent said source of electrons, for injecting electrons from said source into said wave guide structure with linear and orbital components of motion; and means, adjacent said wave guide structure, for establishing a longitudinal magnetic field therein; said magnetic field having a magnitude determined by the expression

$$\frac{10\omega m}{e} \left(1 - \frac{v_e}{v_p} \right)$$

where ω is the angular phase velocity of said electromagnetic energy, m is the electron mass, e is the electron charge, v_e is the linear velocity of said electrons along said wave guide structure, and v_p is the linear phase velocity of said electromagnetic energy.

3. In combination: a wave guide structure adapted to be excited by electromagnetic energy having a predetermined angular phase velocity; a source of electrons; means, adjacent said source of electrons, for injecting electrons from said source into said wave guide structure with an orbital component of motion; means, coupled to said wave guide structure, for separating said electrons into substantially in-phase and out-of-phase groups with respect to said electromagnetic energy; and means, adjacent said wave guide structure, for adjusting the angular velocity of said in-phase group of said electrons to substantially equal the angular phase velocity of said electromagnetic energy.

4. In combination: a wave guide structure adapted to be excited by electromagnetic energy having a predetermined angular phase velocity; a source of electrons; means, adjacent said source of electrons, for injecting electrons from said source into said wave guide structure with linear and orbital components of motion; means, coupled to said wave guide structure, for separating said electrons into substantially in-phase and out-of-phase groups with respect to said electromagnetic energy; and means, adjacent said wave guide structure, for establishing a longitudinal magnetic field therein; said magnetic field having a magnitude determined by the expression

$$\frac{10\omega m}{e} \left(1 - \frac{v_e}{v_p} \right)$$

where ω is the angular phase velocity of said electromagnetic energy, m is the electron mass, e is the electron charge, v_e is the linear velocity of said in-phase group of said electrons along said wave guide structure, and v_p is the linear phase velocity of said electromagnetic energy.

5. In combination: a wave guide structure including a pair of communicating wave guide sections which are perpendicularly disposed with respect to each other and which are adapted to

25

be excited by electromagnetic energy having a predetermined angular phase velocity; means providing a magnetic circuit having a first gap in the region adjacent the junction between said wave guide sections; means, spaced from said last-named means, providing a magnetic circuit having a second gap in a region along the length of one of said wave guide sections; a source of electrons; means, adjacent said source of electrons, for projecting electrons from said source across 10 said first gap in the direction of said second gap with linear and orbital components of motion; the strength of the magnetic fields across said first and second gaps, relative to the linear component of motion of said electrons, being such 15 that the angular velocity of said electrons is substantially equal to the angular phase velocity of said electromagnetic energy; and the effective length of the path of said electromagnetic energy between said first and second gaps being 20 such as to provide a predetermined phase rela-

5

26

tionship between said electromagnetic energy and the orbitally moving electrons arriving in the vicinity of said second gap.
